UNITED STATES PATENT OFFICE.

HARRY M. AMOS, OF RAINSBURG, PENNSYLVANIA.

FRUIT-EVAPORATOR.

SPECIFICATION forming part of Letters Patent No. 595,011, dated December 7, 1897.

Application filed March 11, 1897. Serial No. 627,030. (No model.)

To all whom it may concern:

Be it known that I, HARRY M. AMOS, a citizen of the United States, residing at Rainsburg, in the county of Bedford and State of

5 Pennsylvania, have invented certain new and useful Improvements in Fruit-Evaporators; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to certain new and useful improvements in fruit-evaporators, and especially to an improvement upon my evaporator upon which I was granted Letters Patent No. 556,912 of March 24, 1896; and 20 the present invention is designed to generally improve upon the construction shown in my former patent, by which I produce a more practical evaporator, in which all moisture coming from the tanks is kept from moistening 25 the fruit held in the trays formed upon the tops of each of the superimposed tanks, and making the various trays easily detachable.

More especially the invention resides in the 30 provision of hoops or bands which have outwardly-flaring rims at their upper ends, which are designed to overlap the telescoping funnels which communicate between the tanks, and the provision of an outer hoop forming 35 a receptacle which is soldered to the top or upper surface of each tank, excepting the top one, and surrounds the funnel-shaped passage-way, whereby any moisture which may pass down the sides of the funnels may be 40 conducted back into the tank beneath.

To these ends and to such others as the invention may pertain the same consists, further, in the novel construction, combination, and adaptation of parts, which will be more 45 clearly shown in the accompanying drawings and then specifically defined in the appended claim.

I clearly illustrate my invention in the accompanying drawings, which, with the letters 50 of reference marked thereon, form a part of this specification, and in which drawings

similar letters of reference indicate like parts throughout both views, in which—

Figure 1 is a vertical central section through my improved evaporator. Fig. 2 is a perspective view of two of the trays separated, showing the arrangement of the connecting funnels.

Reference now being had to the details of the drawings by letter, A designates the bottom tank, which is adapted to be partially filled with water for the purpose of heating, and superimposed upon the base portion are the combined trays and tanks B, the bottom of each of the said tanks being provided with 60 legs C, and at the center of the bottom of the said tanks B is provided an aperture through which water and steam are allowed to pass from tank to tank. The bottom of each of the said tanks is also inclined, as shown in 65 the drawings, so as to allow water to readily drain off.

Secured to the periphery of each aperture is a flaring hoop E, which projects downward, and telescoping within the top of said hoop 75 is the band F, having a flange F' about its top overlapping the meeting edges of the said hoop and the portion of the bottom of the tank about the periphery. The said band F is slightly tapered, leaving a sufficient space 80 between its outer circumference and the inner circumference of the ring E to receive the telescoping band or connection G, the lower end of which is designed to be soldered to the top of a tray H. It will thus be seen 85 when one tray is superimposed with the bands and hoops telescoping as described that any moisture which may be contained within the tanks above will readily pass through the apertures to the lower tank without any liability of any moisture passing into the trays 90 from the tanks.

Located about each of the bands or funnel-shaped connections G is a band K, which is provided to receive any moisture that might 95 happen to fall in the space outside of the band G and in the space between the said bands G and K. About the lower portion of each band G are apertures to allow the water to pass through into the passage-way leading 100 from tank to tank. At either corner of the tanks, as at M, are provided outlet-apertures,

provided with suitable caps, having loops M' by which they may be more easily removed.

From the above description it will be noted that each tray may be readily removed, as the 5 telescoping parts will not in any way bind against one another, and will at the same time prevent moisture from entering the drying-trays, which were objections raised against my former invention.

10 Having thus described my invention, what I claim to be new, and desire to secure by Letters Patent, is—

A fruit-evaporator, consisting of a series of superimposed trays, each tray being provided

on its upper surface with a tapering band G 15 apertured near its lower edge and surrounded by a band K, combined with a tapering band secured about the periphery of a central, bottom aperture in the tray, and a flanged hoop telescoping therein, leaving a slight space between the walls of each to receive a hoop G, substantially as shown and described.

In testimony whereof I affix my signature in presence of two witnesses.

HARRY M. AMOS.
